WALL SCRAPER

Glenn D. Johnson, Compton, and Egon R. Lindgren, Huntington Park, Calif., assignors to Baash-Ross Tool Company, Los Angeles, Calif., a corporation of California

Application February 23, 1938, Serial No. 192,044

8 Claims. (Cl. 255—76)

This invention relates to well drilling tools and relates more particularly to expansible reaming or cutting tools of the character known as wall scrapers. A general object of the invention is to 5 provide a practical, dependable and effective hydraulically actuated wall scraper.

Another object of this invention is to provide an underreaming tool or wall scraper in which the cutting elements are controlled or operated 10 by a fluid pressure actuated means that is positive and not subject to failure or premature actuation.

Another object of this invention is to provide a tool of the character mentioned in which the driller or operator is made aware of the projection or actuation of the cutting elements when their 15 projection is complete.

Another object of this invention is to provide a hydraulically actuated wall scraper in which the 20 circulation of the fluid through the operating string and the tool is started simultaneously with complete projection of the cutting elements to inform the driller of this fact and to assure the proper flushing action at the cutting elements.

Another object of this invention is to provide a wall scraper of the character mentioned in which the circulation of fluid cannot be cut off, interrupted or excessively restricted following actuation 25 of the cutting elements.

Another object of this invention is to provide a wall scraper of the character mentioned in which the circulation fluid is fully handled by the piston element following actuation of the cutting elements thereby eliminating the necessity for special passages and ports and materially 30 simplifying the tool.

A further object of this invention is to provide a wall scraper of the character mentioned in which the cutting elements are positioned and related to the movable piston element so that a maximum mechanical advantage is obtained for their actuation or projection.

The various objects and features of our invention will be fully understood from the following 45 detailed description of a typical preferred form of the invention, throughout which description reference is made to the accompanying drawings in which:

Fig. 1 is a side elevation of the tool provided by 50 the invention with a portion broken away to illustrate one of the cutting elements in its retracted position. Fig. 2 is an enlarged longitudinal detailed sectional view of the principal parts of the tool showing the piston and the cutting 55 elements in the normal positions. Fig. 3 is an

enlarged side elevation of the valve removed from the tool with portions broken away to show a latch and illustrating the spring and washers in cross section. Fig. 4 is a view similar to Fig. 3 showing the cutting elements in the projected 5 position and Figs. 5 and 6 are enlarged transverse detailed sectional view taken as indicated by lines 5—5 and 6—6 respectively, on Fig. 4.

The improved underreaming tool or wall scraper of the present invention includes, generally, a body 10, a plurality of cutting elements 11 carried by the body 10, a tubular mandrel 12 shiftable in the body 10 to project the cutting elements 11 and a control 13 cooperable with the mandrel 12 to effect its positive actuation by fluid 10 pressure and providing for the substantially free 15 passage of circulation fluid through the tool when the projection of the cutting elements 11 is complete or substantially complete.

The body 10 of the tool is adapted to be connected with a tubular operating string such as a string S of drill pipe. The body 10 is a hollow tubular structure adapted to contain the mandrel 12 and the control 13 and to handle the circulation fluid. In the preferred construction the body 20 10 is sectional, comprising a tubular upper section 14 and a lower section 15. The upper section 14 is provided at its upper end with a tapered screw-threaded pin 15a for facilitating the connection of the tool with the string S. The upper 25 body section 14 may be a simple tubular member of uniform diameter and of substantially the same diameter as the string S. A tapered socket 16 may be provided in the lower end of the section 14.

The lower body section 15 is an elongate member 30 secured to the lower end of the section 14. In practice the member 15 may be provided with a tapered pin 17 threaded into the socket 16. The two body sections 14 and 15 may be of the same 35 external diameter. The section 15 is provided between its ends with circumferentially spaced longitudinal enlargements or ribs 18. In the form of the invention disclosed there are three equally spaced ribs 18. The tool may carry a suitable 40 bit B. As shown in the drawings the bit B may be secured to the lower end of the section 15 by a suitable threaded connection 19. A longitudinal bore or cylinder opening 20 extends centrally 45 through the section 15 from the upper end of its pin 17. The opening 20 has a diameter considerably less than the diameter of the opening 21a in the upper body section 14. In the preferred construction the opening 20 terminates at a point 50 above the lower end of the section 15.

Elongate openings or slots 21 are provided in the body section 15 to carry or receive the cutting elements 11. The slots 21 extend outwardly from the cylinder opening 20 and pass through the ribs 18 to the external surfaces of the ribs. There is one slot 21 extending through each rib 18. In accordance with the invention the side walls of the slots 21 are tangent to circles concentric with the longitudinal axis of the body 10. These tangential side walls of the slots 21 are preferably flat and vertical. The lower walls of the slots 21 may be flat and horizontal while the upper walls 22 of the slots 21 are preferably inclined downwardly and outwardly with respect to the vertical axis of the tool.

The cutting elements 11 are provided to act on the earth formation to enlarge the well bore below the lower end of a casing set in the well. In accordance with the broader aspects of the invention the cutting elements 11 may be varied in character or type. In the typical embodiment of the invention illustrated the cutting elements 11 are in the nature of shear type or drag type blades. The several blades or elements 11 may be identical. The cutting elements 11 are flat plate-like members and are pivotally supported in the slots 21 and are movable or swingable from retracted positions such as shown in Figs. 1 and 2 of the drawings to projected positions such as shown in Figs. 4 and 5. In the arrangement illustrated in the drawings transverse openings 23 are provided in the ribs 18 to intersect the slots 21 and pins 24 are driven or otherwise fixed in the openings 23 to pass through transverse openings 25 in the cutting elements 11. Thus the cutting elements 11 are supported for pivotal movement about individual horizontal or transverse axes.

The inner ends of the cutting elements 11 may be curved about their pivotal axes. The upper and lower edges 26 and 27 respectively, of the elements 11 may be substantially parallel while the outer ends 28 of the elements are inclined or pitched to join the lower edges 27 at points 29. These points 29 may be somewhat flat to be substantially horizontal when the cutting elements 11 are projected to their active positions. The outer edges 28, the lower edges 27 and the points 29 may be suitably sharpened and may be hard-faced. It will be observed that the cutting elements 11 pivoted in the tangential slots 21 have a desirable lead with respect to the direction of rotation of the tool to be particularly effective in their cutting action.

The mandrel 12 is controlled or actuated by the pressure on the drilling fluid or circulation fluid to swing the cutting elements 11 to their active positions. The mandrel 12 is in the nature of a tubular piston shiftable in the opening 20 of the body section 15. The mandrel 12 is of sufficient length to project a substantial distance upwardly into the body section 14 and yet have a substantial portion received in the opening 20. The central longitudinal opening 30 of the mandrel 12 extends completely through the mandrel to receive the fluid from the interior of the body section 14 and to discharge the circulation fluid at or adjacent the above-described slots 21. The mandrel opening 30 is sufficiently large in diameter to correctly handle the circulation fluid necessary for the flushing of the cutting elements 11.

A head or piston P is provided on the upper end of the mandrel 12 to slidably seat with the interior of the body section 14. The piston P

may comprise a lower plate or member 31 seating downwardly against a shoulder 32 on the mandrel 12, a cup leather 33 at the upper side of the member 31 and a nut 34 threaded on the mandrel 12 and engaging downwardly against the cup leather 33. The cup leather 33 is positioned and designed to effectively seal with the wall of the opening 21a when fluid pressure is applied to the upper side of the piston P. It will be observed that the piston P has an effective diameter considerably greater than that of the opening 30 so that fluid pressure in the opening 21a is operable to move the mandrel 12 downwardly. Bleeder ports 35 are provided in the wall of the section 14 to communicate with the opening 21a adjacent the pin 17 to allow free downward movement of the piston P in the opening 21. The piston member 31 is adapted to engage the upper end of the pin 17 to limit the downward travel of the mandrel 12.

In accordance with the invention the mandrel 12 has active cooperation with the cutting elements 11. It is a feature of the invention that the operative relationship between the mandrel 12 and the cutting elements 11 is such that levers, links, pivotal connections and the like are unnecessary and the mandrel has direct cooperation with parts on the cutting elements. Spaced downwardly projecting fingers 36 are provided on the lower end of the mandrel 12. When three cutting elements 11 are employed there are three equally spaced fingers 36. The lower ends of the fingers 36 are suitably rounded or convex. The opening 30 continues downwardly through the series of fingers 36, that is, the inner surfaces of the fingers are flush with the wall of the opening 30 so that the fingers do not restrict or interfere with the downward flow of fluid. A tail or lug 37 is provided on the inner end of each cutting element 11 and is engageable by a finger 36. The lugs 37 may be integral parts of the cutting elements 11. Considering the cutting elements 11 to be in their retracted positions, the upper sides 38 of the lugs 37 slope downwardly and outwardly relative to the central vertical axis of the tool. The upper sides 38 of the lugs 37 are flat and smooth so that the fingers 36 have effective camming cooperation with the lugs. The lower ends or edges of the lugs 37 may slope downwardly and outwardly considering the elements 11 to be in their retracted positions. The inner sides of the lugs 37 are concave or grooved to be flush with or to be in alignment with the wall of the opening 30 when the elements 11 are in their extended positions so that the lugs do not interfere with the downward flow of fluid from the opening.

It is believed that it will be apparent how the fingers 36 of the mandrel 12 cooperate with the lugs 37 during downward movement of the mandrel to swing the cutting elements 11 from their retracted positions to their expanded or extended cutting positions. It is to be observed that the cutting elements 11 occupy vertical planes tangent to a circle concentric with the vertical axis of the tool so that a desirable leverage or mechanical advantage is obtained for the actuation of the cutting elements. The parts are related so that the piston member 31 approaches or cooperates with the upper end of the pin 17 when the cutting elements 11 reach the positions where their upper edges 26 approach or cooperate with the upper walls 22 of the slots 21. The upper edges 26 of the cutting elements 11 are adapted to have extensive flat engagement with said upper walls 22.

Means is preferably provided to prevent turning of the mandrel 12 to maintain the fingers 36 in correct relation to the lugs 38. One or more circumferentially spaced keys 40 are set in the wall of the opening 20 to be slidably received in keyways 41 in the mandrel 12. The keys 40 are preferably fixed or held in grooves 42 in the wall of the opening 20. In the case illustrated the keys 40 engage against the lower ends of the 10 grooves 42 and the metal of the pin 17 is peened over at 43 to engage downwardly against the upper ends of the keys. The lower walls of the keyways 41 are cooperable with the lower ends of the keys 40 to limit the upward travel of the 15 mandrel 12.

The control 13 is an important feature of the invention. The control 13 provides for the positive actuation of the cutting elements 11 by the mandrel 12 and provides a signal to the driller 20 or operator to indicate the projection or expansion of the cutting elements 11. In the preferred construction the control 13 is housed in the upper body section 14. The control 13 comprises what we will term a valve 44. The valve 25 44 is in the form of an elongate member provided at its lower end with a head 45. The valve 44 is arranged centrally and longitudinally in the section 14 and is guided for vertical movement by a web or guide 46. The guide 46 may 30 be a ring-like member threaded in the opening 21^a and is provided with a central vertical opening 47 slidably passing the valve 44. The guide 46 is perforated to provide for the free flow of circulation fluid through the opening 21^a. The valve 44 is co-axial with the mandrel 12 and its head 45 is cooperable with a valve seat 48 on the mandrel. The seat 48 may be a tubular member extending into the opening 30 and may have a flange 49 clamped against the upper end of the 35 mandrel 12 by the nut 34. The valve head 45 is adapted to engage downwardly against the upper end of the seat 48 to close off the opening 30. The head 45 is pointed or tapered to extend downwardly into the seat 48 and to cooperate with a suitable bevelled surface on the seat.

When the parts are in their "initial" positions just prior to expansion of the cutting element 11, the mandrel 12 is in the position where its piston 50 P is some distance above the pin 17 and the valve 44 has its head 45 in cooperation with the seat 48 to close the opening 30. The valve 44 is adapted to follow or move downwardly with the mandrel 12 when pump pressure is applied to the fluid in 55 the string S so that the piston P and the valve 44 form a solid or imperforate assembly against which the fluid pressure acts to effect the positive actuation of the cutting elements 11.

The control 13 includes a novel mechanism 60 for retracting or freeing the valve 44 from the mandrel 12 and its seat 48 when the mandrel reaches or approaches a position where the cutting elements 11 are fully extended. This mechanism includes a helical spring 50 carried by the 65 valve 44. The spring 50 surrounds the upper portion of the valve 44 and is located above the guide 46. A nut 51 may be threaded on the upper end of the valve 44 and the upper end of the spring 50 may engage against a washer 52 bearing upwardly against the lower end of the nut. The lower end of the spring 50 cooperates with a 70 ring 53. The ring 53 is slidable or shiftable on the valve 44 and is provided with an upturned rim 54 for holding the spring 50 centralized.

75 A latch 55 is provided on the valve 44 to ini-

tially or normally hold the ring 53 in a position where the spring 50 is under compression or is contracted. The latch 55 may be arranged in a slot 56 in the valve 44 and may be pivotally supported by a pin 57 passing transversely through the slot. The latch 55 projects upwardly and outwardly from its pivot pin 57 to protrude from the slot 56 and its upper end is adapted to cooperate with the lower side of the ring 53. The engagement of the upper end of the latch 55 10 with the lower side of the ring 53 holds the ring against downward movement on the valve 44 and therefore maintains the spring 50 under substantial compression between the ring and the washer 52. A shoulder 58 may be provided on 15 the upper end of the latch 55 to cooperate with the internal surface of the ring 53 to prevent premature displacement or disengagement of the latch from the ring.

The latch 55 is positioned so that its inclined 20 outer edge cooperates with the wall of the opening 47 during downward movement of the valve 44 with the mandrel 12. This engagement of the latch 55 with the wall of the opening 47 occurs when the mandrel 12 approaches the position where the cutting elements 11 are fully 25 actuated and occurs when the lower side of the ring 53 approaches or engages the upper side of the guide 46. The engagement of the sloping outer edge of the latch 55 with the wall of the opening 47 results in retraction of the latch substantially simultaneously with the cooperation of the ring 53 with the upper side of the guide 46. The release of the latch 55 from the ring 53 occurs when the piston P is a short distance 30 above the upper end of the pin 17 and the cutting elements 11 are substantially fully projected. The release of the latch 55 from the ring 53 frees the valve 44 from the ring 53 so that the spring 50 reacting against the ring (now seated on the 35 guide 46) and reacting against the washer 52 suddenly moves the valve 44 upwardly. The broken lines in Fig. 4 indicate the lowermost position attained by the valve 44. When this position is attained by the valve 44, the latch 55 is 40 released, as described above, and the spring 50 moves the valve 44 upwardly away from the seat 48 and the piston P to allow or initiate the discharge of the fluid under pressure downwardly through the opening 30 of the mandrel 12. This 45 initiation of the circulation of fluid is accompanied by a starting of the pumps handling the fluid so that the driller is automatically informed of the actuation of the cutting elements 11. A collar 60 may be fixed to the valve 44 above the 50 ring 53 to cooperate with the ring and cause the ring to engage against the guide 46 and thereby 55 definitely limit the downward travel of the valve 44.

The control 13 further includes latch means 60 for retaining the valve 44 in the up or released position following its retraction by the spring 50 as just described. A longitudinal slot 61 is provided in the ring 53 and a latch 62 is arranged in the slot. The latch 62 is pivotally supported 65 on a pin 63 extending transversely through the slot 61. The latch 62 projects upwardly from its pivot pin 63 and is adapted to project from the inner wall or surface of the ring 53. A spring 64 is secured to the ring 53 and cooperates with 70 the latch 62 to yieldingly urge the latch inwardly. The latch 62 may normally yieldingly bear on the valve 44.

An annular groove 9 having a downwardly facing wall is provided in the valve 44. The 75

- groove 9 is located to move upwardly through the opening 47 to a position above the guide 46 when the spring 50 shifts the valve 44 upwardly as described above. The latch 62 is cooperable 5 with the groove 9 when the groove moves through or into the ring 53 seated on the guide 46 as described above. The spring 64 automatically moves the latch 62 into cooperation with the groove 9 so that the groove and latch cooperate as illustrated in Fig. 4 of the drawings. 10 This cooperation of the latch 62 with the groove 9 holds the valve 44 in its retracted position and positively prevents downward movement of the valve following the actuation of the cutting elements 11. 15
- In the operation of the tool the body 10 carrying the bit B may be secured to the lower end of the string S and run into the well on the string. The parts are in the positions illustrated 20 in Fig. 2 of the drawings when the tool is run into the well. In the event that the well contains liquid the string S may be run into the well "wet", that is, filled with liquid so that the hydrostatic forces on the valve 44 and mandrel 12 are balanced. In most instances, however, it may be preferred to run the tool into the well "dry" so that the well liquid flows up through the opening 30 and raises the valve 44 to enter the string S. The hydrostatic pressures acting on the lower 25 end of the mandrel 12 may also raise the mandrel. This upward movement of the mandrel 12 is limited by the lower walls of the keyways 41 cooperating with the keys 40. The hydrostatic pressure in the well may be sufficient to 30 raise the valve head 45 from its seat 48 when the upward movement of the mandrel 12 has stopped. When the pressures on the mandrel 12 and valve 44 have become equalized the valve 44 and the mandrel 12 return by gravity to the positions 35 illustrated in Fig. 2.
- When the well scraper or tool has reached a 40 position beyond the lower end of the well casing rotation of the tool is begun. The fluid in the string S is then put under pressure by the pumps. The fluid pressure in the opening 21 acts downwardly against the piston P and the valve 44 to move the same downwardly. During the downward movement of the mandrel 12 the fingers 36 of the mandrel cooperate with the lugs 37 to swing the cutting elements 11 to their 45 projecting positions. The expanding cutting elements 11 on the rotating tool cut clearance in the earth formation at the side wall of the well. The downward movement of the mandrel 12 and the valve 44 continues until the latch 55 moves through or into the opening 47. The engagement 50 of the wall of the opening 47 with the latch 55 retracts the latch and, upon retraction of the latch from the ring 53, the spring 50 reacting against the upper side of the guide 46 through the medium of the ring 53 suddenly moves the valve 44 upwardly. This moves the valve head 45 away from the seat 48 and allows the fluid under pressure to flow downwardly through the opening 30. The piston P and the mandrel 12 55 may continue to move downwardly. The fluid is free to discharge into the well through the slots 21 at or adjacent the plane of action of the cutting elements 11. The piston P and the mandrel 12 60 may continue to move downwardly under the action of the fluid pressure after the valve 44 is retracted as just described. During the upward movement of the valve 44 its groove 9 moves through or into the ring 53 and when the valve approaches its uppermost position the latch 65

62 pivots inwardly under the action of the spring 64 so that its upper inner corner engages in the groove 9. This latches the valve 44 in its raised position.

The upward movement of the valve 44 away 5 from the piston P and the valve seat 48 allows the circulation fluid to flow downwardly through the opening 30 and out through the slots 21. This initiation of the circulation through the tool results in the starting of the pumps and this informs the operator or driller of the projection of the cutting elements 11. The rotation of the string S may be continued to cause the cutting elements 11 to ream or enlarge the bore as desired. During this reaming action the circulation fluid is pumped downwardly through the string S to flow through the openings 21a and 30 to discharge from the slots 21. The fluid discharging from the slots 21 effectively cleans and flushes the cutting elements 11 and may assist in the reaming operation. It will be observed that the opening 30 is clear and unobstructed following the retraction of the valve 44 and that the circulation fluid may freely flow out through the slots 21. 15

The present invention provides a reaming tool or wall scraper in which the cutting elements are positively projected or actuated by a hydraulic means and in which the driller or operator is made aware of the correct projection of the cutting elements. There is a minimum obstruction to the circulation of fluid through the tool following the projection of the cutting elements 11 and the fluid is conducted or handled by the simple tubular mandrel 12 without resorting to 20 the use of special passages and ports in the tool body. 25

Having described only a typical preferred form and application of our invention we do not wish to be limited or restricted to the specific form and application herein set forth, but wish to reserve to ourselves any modifications or variations that may appear to those skilled in the art or fall within the scope of the following claims. 40

Having described our invention, we claim:

1. A well tool of the character described comprising a body, a cutting element carried by the body for movement from a retracted position to a projecting position, a tubular piston element movable in the body by fluid pressure to project the cutting element, a valve closing the piston element and movable therewith, and means operable to move the valve in a direction opposite to the direction of travel of the piston element to permit flow through the piston element when the cutting element is projected. 50

2. A well tool for use on a tubular well string comprising a hollow body having communication with the string, a cutting element carried by the body for movement from a retracted position to a projecting position, a tubular piston element movable downwardly in the body by fluid pressure applied through the string to move the cutting element to a projecting position, a valve in the body closing the piston element and movable therewith during said projection of the cutting element, and means for moving the valve upwardly away from the piston element when the cutting element is projected to initiate the flow 65 of fluid through the piston element. 70

3. A well tool for use on a tubular well string comprising a hollow body having communication with the string, a cutting element carried by the body for movement from a retracted position to 75

5 a projecting position, a tubular piston element movable in the body by fluid pressure applied through the string to move the cutting element to a projecting position, a valve in the body closing the piston element and movable therewith during said projection of the cutting element, and spring means moving the valve away from the piston to allow the fluid to flow therethrough when the cutting element is projected.

10 4. A well tool for use on a tubular well string comprising a hollow body having communication with the string, a cutting element carried by the body for movement from a retracted position to a projecting position, a tubular piston element movable in the body by fluid pressure applied through the string to move the cutting element to a projecting position, a valve in the body closing the piston element and movable therewith during said projection of the cutting element, 15 means for reversing the direction of travel of the valve to move the valve away from the piston to allow the fluid to flow therethrough when the cutting element is projected, and means for subsequently holding the valve in a retracted 20 position.

25 5. A well tool of the character described for use on a tubular well string comprising a hollow body having communication with the string the body having a cylinder opening and spaced lateral 30 slots joining the cylinder opening and lying in planes tangent to a circle concentric with the longitudinal axis of the body, cutting elements pivoted in the slots, and means for swinging the cutting elements to positions where they project from the slots including a tubular fluid conducting piston element movable in said opening by fluid pressure, the lower end of the piston element initially discharging freely into the cylinder opening above the slots and discharging at 35 40 the slots when the element is actuated, lugs on the inner ends of the cutting elements, and spaced downwardly projecting parts on the lower end of the piston element engaging the lugs to swing the cutting elements when the piston element moves, the slots receiving fluid from the lower end of the piston element and discharging into 45 the well.

50 6. A wall scraper for use on a tubular well string including a body having an opening communicating with the string and a second opening extending downwardly from the first opening and having a lateral slot joining said second opening, a cutting element pivoted in the slot to be projected therefrom, a tubular mandrel shiftable in the said second opening and mov-

able to project the cutting element, a piston on the mandrel movable downwardly in the said first opening by pressure applied through the string, a valve closing the tubular mandrel and movable therewith during projection of the cutting element, and means for moving the valve upwardly from the mandrel when the cutting element is projected so that fluid may pass through the mandrel and discharge from the slot.

5 10 7. A wall scraper for use on a tubular well string including a body having an opening communicating with the string and a second opening extending downwardly from the first opening and having a lateral slot joining said second opening, a cutting element pivoted in the slot to be projected therefrom, a tubular mandrel shiftable in the said second opening and movable to project the cutting element, a piston on the mandrel operable in the said first opening 15 by pressure applied through the string, a valve closing the tubular mandrel and movable therewith during projection of the cutting element, and means for automatically retracting the valve from the mandrel when the cutting element is 20 projected so that fluid may pass through the mandrel and discharge from the slot, said means comprising a relatively stationary abutment in the body, a shiftable member on the valve engageable with the abutment, a spring arranged 25 under compression between said member and a part of the valve, and a latch on the valve normally holding the said member in a position where the spring is compressed and released by engagement with the abutment to permit the 30 spring to react against the abutment to move the valve.

8. A well tool for use on a tubular well string comprising a hollow body having communication with the string, a cutting element carried by the body for movement from a retracted position to a projecting position, a tubular piston element movable in the body by fluid pressure applied through the string to move the cutting element to a projecting position, a valve in the body 40 closing the piston element and movable therewith during said projection of the cutting element, a member in the body guiding the valve, and means for retracting the valve from the piston element when the cutting element is projected 45 including spring means for reacting between the valve and the guide member, and latch means 50 controlling the spring means.

GLENN D. JOHNSON.
